BATH SHOWER HEAD

James D. Crenshaw, Webster Groves, Mo.

Application January 22, 1954, Serial No. 28,628

Term of patent 14 years

(Cl. D91—3)

FIG. 1.

FIG. 2.

FIG. 3.

To all whom it may concern:

Be it known that I, James D. Crenshaw, a citizen of the United States and a resident of Webster Groves, St. Louis County, Missouri, have invented a new, original, and ornamental Design for a Bath Shower Head, of which the following is a specification, reference being had to the accompanying drawing, forming part hereof, in which:

Fig. 1 is a side elevation of a bath shower head embodying my new design;

Fig. 2 is a front elevation of Fig. 1; and,

Fig. 3 is a top plan view.

The broken lines are for the purpose of illustration only.

I claim:

The ornamental design for a bath shower head, substantially as shown and described.
